UNITED STATES PATENT OFFICE.

ROBERT B. McMASTERS, OF MARATHON, NEW YORK.

MITTEN.

No. 797,212.

Specification of Letters Patent.

Patented Aug. 15, 1905.

Application filed December 2, 1904. Serial No. 235,236.

To all whom it may concern:

Be it known that I, ROBERT B. McMASTERS, a citizen of the United States, residing at Marathon, in the county of Cortland and State of New York, have invented certain new and useful Improvements in Mittens; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in mittens; and the object of the invention is to produce an article of this character which will be of a substantial nature and one which is practically seamless at the points which receive the greatest wear or service.

The invention consists, further, in various details of construction and combinations and arrangements of parts, which will be herein-after fully described and then specifically defined in the appended claims.

My invention is illustrated in the accompanying drawings, in which—

Figure 1 is a plan view of a blank of leather or other suitable material from which the mitten is made. Fig. 2 is a similar view showing the first step in the folding of the end flaps of the blank. Fig. 3 is a similar view showing the end and side flaps folded and stitched, forming the back of the mitten. Fig. 4 is a plan view of a blank of modified form of mitten. Fig. 5 is a detail view showing the end flaps folded in; and Fig. 6 is a detail view showing the side and covering flaps for the ends folded and stitched, the illustrations of the folded sections being the rear or back parts of the mitten.

Reference now being had to the details of the drawings by letter, A designates a blank of leather or other suitable material having flaps B, C, D, E, and F radiating from one end of the blank. Each of said flaps is tapered, as illustrated, and A² designates longitudinal side flaps, which are adapted to be bent along the lines X X upon themselves, and each of said flaps is substantially one-half the width of the portion A, which forms the palm of the mitten, whereby when they are folded with the edge of one upon the other they may be stitched together. In stitching the blank to form the mitten the radial flaps are all bent in along the dotted line indicated by letters K, in which folded relation the adjacent longitudi-

dinal edges of the radial flaps will be in contact with each other and stitched, said stitching being illustrated in the drawings by letter N. After the various radial flaps have been stitched from the dotted line to the free ends thereof along their adjacent longitudinal edges the flaps A² are folded in one upon the other, with their forward ends overlapping the stitched ends of said radial flaps, and said side flaps are stitched along their longitudinal overlapping edges, as at M. By this construction it will be observed that a practically seamless mitten is produced at the point where strain and wear come upon the mitten.

In Fig. 4 of the drawings I have shown a slight modification in the form of my improved blank for mittens, in which the body portion A is adapted to form the palm of the mitten and two side flaps A⁴ are adapted to be folded upon the dotted line a, so that the inner longitudinal edges of said side flaps will overlap and receive a stitching a' in the same manner as illustrated in Figs. 1 to 3, inclusive. In the modified forms the radial flaps B', C', and D' are folded in, so that their adjacent edges will be in contact with each other, and an additional semicircular flap O, which is integral with the end of the blank, is folded over the inturned radial and side flaps and stitched along the dotted line designated by letter Q, thereby forming a seamless end to the mitten. In order to further reinforce the inturned flaps, I apply staples P, which are passed through the flap O and clenched to the inturned radial flaps as well as to the side flaps, thus more securely holding the parts in their folded relations than would be the case without the staples.

While I have shown a particular construction of mitten illustrating my invention, it will be understood that I may vary the same as to details of construction, if desired, without in any way departing from the spirit of the invention.

Having thus fully described my invention, what I claim as new, and desire to secure by Letters Patent, is—

1. A mitten made of a single blank having radial flaps at one end with inclined edges designed to be folded in upon the blank and stitched together, side flaps adapted to be folded to form the back of the mitten, with the meeting edges of said side flaps overlapping and designed to be stitched together and to said folded radial flaps, as set forth.
2. A mitten made of a single blank of ma-

terial having radial and side flaps, the latter adapted to be folded to form the back of the mitten, the meeting edges of said side flaps overlapping and designed to be stitched together, said radial flaps adapted to be folded upon the inner face of the palm of the mitten and stitched together, a semicircular flap at the end of the palm portion of the mitten designed to fold over said inturned radial flaps and with the outer marginal edge of said end flap even with the folded portions of the ra-

dial flaps and designed to be stitched over the ends of the side flaps, thereby producing an essentially seamless mitten at the points where the greatest wear comes upon the mitten, as set forth.

In testimony whereof I hereunto affix my signature in presence of two witnesses.

ROBERT B. McMASTERS.
